TYPEWRITING MACHINE

Elmer L. Wise, Bridgeport, Conn., assignor to
Underwood Elliott Fisher Company, New York,
N. Y., a corporation of Delaware

Application March 13, 1936, Serial No. 68,648

8 Claims. (Cl. 197—36)

This invention relates to typewriting machines and more particularly to the type bars thereof.

Heretofore, it has been proposed to provide typewriting machines with one or more sectional type bars, the sections of which are releasably connected, the outermost section terminating at its free end in a hollow rectangular holder, head or chase to removably accommodate a series of single types to represent, for instance, a date, as 10 "Feb. 29, 1936", or an abbreviation as "Mdse" or "Cash".

Suitable means is provided to releasably retain the types in place, so that the operator may set types to represent any desired date, abbreviation 15 or other wording.

The characters forming the date or abbreviation designation occupy a plurality of letter spaces, and suitable means forming no part of the present invention, is provided to automatically 20 effect an abnormal letter spacing travel of the carriage when the date or other plurality of simultaneously printed letters is printed in its appropriate column.

One disadvantage residing in the above structure is that the individual type bodies composing the date, abbreviation or other designation become somewhat worn, after a time, due to repeated placing in and removal from the holder, as a result of which, it is difficult to hold them in 30 perfect alignment relatively to each other.

Hence, the imprints are not as symmetrical and nice-appearing as the remainder of the printed matter in that line.

The present invention is an improvement on 35 the preceding structure, one object being to provide a removably held date or abbreviation designation, the characters composing which shall always retain their alignment and space intervals, regardless of the number of times the particular 40 designation is inserted in and removed from the holder.

Other objects and advantages will be more fully set forth hereinafter and particularly pointed out in the claims.

45 In the accompanying drawing:

Fig. 1 is a view in side elevation of a sectional type bar, and its key mechanism, with which this invention is conveniently associated;

50 Fig. 2 is an enlarged vertical transverse sectional view of the improved logotype holding device, taken on line 2—2 of Fig. 1;

Fig. 3 is an enlarged vertical sectional view taken on line 3—3 of Fig. 2;

Fig. 4 is a bottom plan view, and

55 Fig. 5 is a greatly enlarged detail perspective

view of a single one of a set of types for insertion into and removal from the type holder.

The invention is shown applied to a flat bed writing machine of the Elliott Fisher type, but its use is not restricted to machines of that class.

Customarily, because of the extended letter space interval covered by the imprint of a plurality of type faces simultaneously on the work sheet, the special type head or holder for such types is arranged for operation by a special key 5 located at one extreme side of the keyboard field.

This key, in turn, is linked to a type bar located preferably near either end of the supporting type segment, so that when the type bar is in actuated position, it, together with its types, 15 will lie substantially parallel with the line of writing, as shown in Fig. 1, thus avoiding the necessity of arranging the type head or holder 20 skewed relatively to the longitudinal axis of the type bar, with the attendant disadvantages, such as interference with the other type bars of the set, for one.

With the foregoing in mind, depression of the special key lever 10, (Fig. 1), pivoted on the usual fulcrum bar 11, thrusts a link or push rod 12 downwardly, to rock the rear end of an intermediate lever 13, fulcrumed at 14 to the upper 25 end of a post 15 projecting upwardly from the supporting deck 16 of the carriage.

The supporting deck 16 is substantially semi-circular in plan view, or is semi-circularly recessed, so that the forward ends of the intermediate levers 13 overhang the recessed portion.

A draw link 17 connects the forward end of the intermediate lever 13 with a bell-crank lever 18, 35 one arm of which is pivoted at 19 to a hanger 20 depending from the bottom face of the supporting deck 16, an adjustable link or turn buckle 21 connecting the bell crank lever 18 with the tail of a type stock or bar 22 pivoted at 23 to a bracket 24 40 fastened to the type segment ring 25.

Hence, upon depression of the key 10, and the consequent rocking of the intermediate lever 13, the draw link 17 is raised to rock the bell crank lever 18, and through the adjustable link or turn 45 buckle 21, to swing the normally vertical type stock or bar downwardly to the position shown in Fig. 1, against the tension of its restoring spring 26, to effect the imprint of the type mounted on the type bar, on the work sheet supported 50 by the platen 27.

Release of pressure on the key lever 10 enables the spring 26 to restore the type action to normal position, assisted by a key lever restoring spring, (not shown), all as more fully described and illus- 55

trated in U. S. patent to Foothorap, 1,251,361, issued December 25, 1917.

In the present instance, the type bar is made sectional, the outer end of the stock 22 being grooved on its opposite edges to removably accommodate a jaw member 30 carrying at its outer end a hollow type bar head or holder 31, of rectangular form, open at one edge to form a pocket.

Suitable means, as a spring clip, releasably connects the stock and jaw member.

Heretofore, separate types, (see Fig. 5), were assembled in the type holder or head 31 by the operator as required, the types being placed in and removed from the hollow head or holder one by one, preferably with the aid of tweezers, and after the holder is filled, a bail 32 of resilient material, pivoted at its ends in the end walls adjacent the bottom of the holder, is swung down to enter grooves in the sides of the type bodies, the side arms of the bail being sprung past bosses 33 projecting from the opposite ends of the holder 31 to hold the bail effective to retain the individual types in assembled position in the holder.

A roll 34 seated in the holder and journaled on the inwardly projecting pivoted ends of the bail serves to protect the inner ends of the latching bail from injury by the inner ends of the types and also affords a stop to uniformly limit the extents to which the individual types can be inserted in the holder, to maintain the several type faces level.

When it is desired to change the designation, the operator must first spring the resilient bail 32 forwardly over the bosses 33 to release the individual types, shown in Fig. 5, which types are then removed, others inserted, and the bail restored to effective position.

The foregoing is old and constitutes a part of this invention only insofar as it co-acts with the novel features hereinafter set forth.

The individual types being often cast or made from a relatively soft metal, became worn after a series of insertions into and removals from the type holder 31.

Furthermore, because of the necessity for forming the holder of sufficient size to enable the ready insertion and removal of the types by unskilled operators, a little wear only, in addition to such clearance, soon results in a "cocking" of the individual types so that they lie at slight angles to each other, and the consequent imprint was unsightly.

The present invention is designed to avoid these and other disadvantages, by providing a filler piece or block 35 preferably of a metal less liable to wear than the metal of which the types are made, and of a size and shape to fit into the type head or holder 31.

A tapered seat 36 is formed transversely of the block 35, the larger end of which seat is located in the exposed edge of the block, and preferably near that end of the block farthest from the type stock 22, the restricted inner end of the seat communicating with an intersecting aperture 37 formed through the block from side to side thereof.

The tapered seat 36 accommodates the similarly tapered stem 38 formed integrally with a type body 39 extending at right angles to the stem and having a plurality of types on its lower or printing face to represent a word, abbreviation, date or what not, constituting a logotype.

The type stem 38 has a driving fit with the tapered seat 36, the stem conveniently being of sufficient length to completely fill the seat, so that

its reduced end enters the intersecting aperture 37 when the logotype is driven home.

The type block 35 with its attached logotype 39 may be readily placed in and moved from the type holder 31, as a unit, by the operator of the machine, without the aid of tools, the block being of such width that its outer edge from which the logotype 39 projects, protrudes beyond the open end of the type holder 31, when the inner edge of the block rests against the limiting roll 34.

A groove 40, (Figs. 2 and 4), extending longitudinally along one side of the protruding portion of the block enables the latching bail 32 to releasably retain the type block and its logotype in place, in the manner heretofore explained.

The positioning of the logotype 39 in its seat in the type block 35 is preferably performed at the factory to insure that the types thereon shall effect an imprint in perfect alignment with the types on the individual type bars of the writing machine, it being possible to provide the logotype with type faces corresponding in size with the individual types on the regular type bars of the machine, whereas the separate types set up in the type holder 31 are of smaller size than the regular types, because it is impracticable to provide a type holder of sufficient size to hold date types (for instance) of a size corresponding with the regular types without interference with the operation of those type bars lying adjacent the special type bar holder.

Entry of a suitable tool into the aperture 37 enables the repairman to release the logotype stem 38 from its seat 36, in case of breakage or for the purpose of inserting a logotype bearing different types, but this operation is not recommended for the average machine operator.

Instead, a set of type blocks 35, each having seated therein a different logotype may be conveniently provided for insertion and removal as a unit relatively to the type holder 31.

The logotype 39 is offset relatively to a line drawn vertically through the longitudinal center of the block (Fig. 3) so as to space the impression of the first type of the logotype sufficiently far away from the impression of the final letter of the preceding word as not to overlap such last named impression.

In other words, if the logotype key lever 10 is depressed immediately after the letter key used in printing the final letter of the preceding word, no intervening letter spacing stroke being taken, the first letter of the logotype will be spaced the same distance from the final letter of the preceding word that the letters of such preceding, or any other word, are spaced from each other.

Obviously, the same type holder 31 may be used to contain a plurality of individual types to represent any desired indication, and also to removably accommodate a type block 35 bearing a stemmed logotype 39, according to the work to be typed.

Changes may be made in the form and arrangement of the several parts described without departing from the spirit and scope of the invention.

What is claimed as new, is:

1. In a typewriting machine, the combination with a selective key action, including a type bar, having a type head formed to accommodate a plurality of individual types at one time; and means to releasably retain the types assembled with the type head; of means to adapt the multiple type head for the assembly therewith of a single printing member bearing a plurality of

type faces, such means including a type block removably accommodated in and filling the type head, and with which alone the releasable, retaining means co-acts; and a single type member mounted in the type block and having a plurality of type faces.

2. The combination with a type head formed to accommodate at one time, a plurality of individual types; and means to releasably retain the several types and the head assembled; of means to adapt the multiple type head for use with a logotype member, including a type block removably held in the type head by the retaining means, the type block having an opening in its outer edge; and a stemmed logotype, the stem of which seats in the opening.

3. The combination with a type head formed to accommodate a plurality of separate and individual types at once; and means to releasably retain the types and type head assembled; of means to adapt the multiple type head for use with a single printing member, including a type block removably accommodated in and filling the type head, with which removable block the releasable retaining means co-acts to retain the type head and type block assembled, the type block having an opening therein; and a stemmed type member, the stem of which is seated in the opening.

30 4. The combination with a type head formed to accommodate a plurality of separate and individual types at once; and means to releasably retain the types and type head assembled; of means to adapt the multiple type head for use with a single printing member, including a type block removably accommodated in and filling the type head, with which removable block the releasable retaining means co-acts to retain the type head and type block assembled, the type block having an opening therein; intersected by an aperture formed transversely of the type block.

5. The combination with a type head formed to accommodate at one time a plurality of indi-

vidual types having grooved sides; and a resilient bail mounted on the type head and adapted to enter the alined grooves to releasably retain the several types and the head assembled; of means to adapt the multiple type head for use with a single printing member, including a grooved type block removably accommodated in, and filling the type head, the resilient bail being accommodated in the groove in the type block to retain the type block and type head assembled, the type block having an opening in its outer edge; and a stemmed type member, the stem of which is seated in the opening.

6. In a type bar, the combination with a holder open along one edge; a type block removably accommodated in the holder; means to releasably retain the holder and block assembled, the type block having a tapered seat formed in its outer edge offset from the center of the block.

7. In a writing machine, having selective keys, and a type bar having a boxlike holder formed at its free end, and open along one edge; the combination of a filler piece shaped to conform to the shape of the boxlike holder and removably accommodated in the holder, the filler piece having a seat formed in its outer edge; means to releasably retain the filler piece within the holder; and a logotype frictionally mounted in the seat in the outer edge of the filler piece, and off-set relatively to one diameter of the holder and filler piece.

8. In a writing machine, having selective keys, and a type bar having a boxlike holder formed at its free end, and open along one edge; the combination of a filler piece shaped to conform to the shape of the boxlike holder and removably accommodated in the holder, the filler piece having a seat formed in its outer edge, and offset relatively to the center of the holder and filler piece; means to releasably retain the filler piece within the holder; and a logotype having a projection frictionally engaging the seat in the filler piece.

ELMER L. WISE.
